UNITED STATES PATENT OFFICE.

WILLIAM B. McDONALD, OF CHICAGO, ILLINOIS.

DESIGN FOR AN INSULATING-PLATE FOR ELECTRIC LAMPS.

SPECIFICATION forming part of Design No. 31,970, dated December 12, 1890.

Application filed November 6, 1899. Serial No. 736,058. Term of patent 7 years.

To all whom it may concern:

Be it known that I, WILLIAM B. McDONALD, a citizen of the United States, and a resident of Chicago, Cook county, Illinois, have invented and produced a certain new and original Design for Insulating-Plates for Electric Lamps, of which the following is a specification, reference being had to the accompanying drawings, forming part thereof.

10 In the drawings, Figure 1 is a plan view of the under side of an insulating-plate, showing my new design. Fig. 2 is a longitudinal central section of the same. Fig. 3 is a plan view of the upper side of said plate, and Fig. 4 is a 15 central transverse section thereof.

As shown in the drawings, the principal or leading features of my design consist of a rectangular glass or vitreous plate A, having the edges *a a* of its under side truncated and having its upper side depressed so as to leave in relief a surrounding marginal wall *b b* and a series of bosses, which surround the openings in the same. In the center of said plate is a large opening B, having a slightly-tapering 25 cylindrical boss c surrounding the upper portion thereof, the projection of which does not extend quite to the horizontal plane of the edge of the marginal wall *b*. Near each end of the plate, in alinement with the center of opening B, are vertical holes C C, the upper portions of which are countersunk. Near each 30 end of the plate and between holes C C and opening B, but nearer the former, are a se-

ries of holes D, E, and F, arranged in transverse alinement. Holes D and E are located 35 near each other on one side of the longitudinal plane of opening B, and opening F is located on the opposite side of said plane. A transversely-elongated boss d, extending from the nearest longitudinal side of marginal wall 40 *b*, surrounds and is pierced by holes D and E, and the rounded end of this boss d is connected by a short neck to the rounded end of a longitudinally-elongated boss e, extending from the end portion of marginal wall *b*, in 45 which holes C are made. Directly opposite and alining with boss d is a short boss f, extending transversely from the side portion of wall *b* through which the hole F is extended. These bosses c and D E F are, it will be no- 50 ticed, made in the depressed area of the upper side of the plate, and the bosses d and f and holes D E F therein at one end are arranged in reverse or transposed order to those at the opposite end of the plate.

Having described my invention, what I claim as new, and desire to secure by Letters Patent, is—

The design for an insulating-plate for electric lamps, as herein shown and described. 60

In testimony whereof I have signed my name in the presence of two witnesses.

WILLIAM B. McDONALD.
